Des. 208,875
Patented Oct. 10, 1967

208,875

SCREW CAP OPENER

Victor G. Fiegel, 248 W. Centralia, St.,
Elkhorn, Wis. 53121

Filed Dec. 5, 1966, Ser. No. 4,967

Term of patent 14 years

(Cl. D44—29)

FIG. 1 is a top plan view of a screw cap opener showing my new design;

FIG. 2 is a bottom plan view;

FIG. 3 is an edge elevational view;

FIG. 4 is an enlarged scale sectional view taken on line 4-4 of FIG. 1; and

FIG. 5 is an enlarged scale sectional view taken on line 5-5 of FIG. 1.

I claim:

The ornamental design for a screw cap opener, as shown.
